[57] CLAIM

The ornamental design for a reusable tray for the growing of seedlings, as shown and described.

DESCRIPTION

FIG. 1 is a perspective view of a reusable tray for the growing of seedlings showing my new design;

FIG. 2 is a bottom plan view thereof;

FIG. 3 is a rear elevation thereof; the front elevation being a mirror image thereof;

FIG. 4 is a left side elevation thereof; the right side elevation being a mirror image thereof;

FIG. 5 is an enlarged fragmentary perspective view taken in the direction of line 5 in FIG. 1; and,

FIG. 6 is an enlarged fragmentary section taken along line 6—6 of FIG. 4.

Fig. 1.
